(57) CLAIM

The ornamental design for a chest, as shown and described.

DESCRIPTION

FIG. 1 is a front perspective view of a chest showing my new design;

FIG. 2 is a front view thereof;

FIG. 3 is a side view, the opposite side being a mirror image; and,

FIG. 4 is a top view thereof.

The broken lines showing the drawer hardware and the feet on the chest are for illustrative purposes only and form no part of the claimed design.

1 Claim, 4 Drawing Sheets
